UNITED STATES PATENT OFFICE

CLARENCE A. RICH, OF LYNN, MASSACHUSETTS

METHOD OF SIGNALING TRAFFIC BY A HAND DEVICE

Application filed May 5, 1926. Serial No. 108,867.

The invention relates to a method of signaling traffic by a hand device of the type which is secured to the hands of an officer for controlling and directing traffic on the highways or other places. The invention consists of a harness secured to the hands of an officer, having lamps projecting varicolored lights, such as red indicating "danger" or "stop", while a green light indicates "safety" or "go." The lamps receive their power preferably from an electrical source. These signal lights are so arranged as to conform to the natural direction or swinging movement of the hands and arms and can be readily recognized by operators of oncoming vehicles in both directions.

The invention further relates to a method of controlling hand signaling lamps by mercury switches which will operate one lamp and open the electrical circuit of the other lamp while one is being used.

The object of the invention is to provide signal lights of different colors to be used at night or in foggy weather by traffic officers, which will definitely indicate "danger" or "stop", or "safety" or "go". Danger signals are commonly used by traffic officers, but when the red light is out of view the operators of vehicles find it difficult to keep track of the officer when he is signaling in the opposite direction, but when lights are used, one of which signals "danger" or "stop" in one direction, and another light signals "safety" or "go", vehicles in both or all directions are protected.

A further object of the invention consists of providing switches which will automatically operate by the movement of the hands and the arms, which will operate one and close the other in order of use and also to close when neither are in use, thereby saving a very large per cent of the electric energy necessary to operate the lamps.

Referring to the figures,

Fig. 1 shows the improved signaling device secured to the hand of an officer with the red light or danger signal projecting;

Fig. 2 shows the arm of the officer bent back upon itself with the signaling device in

position and the green light projecting indicating "safety" or "go";

Fig. 3 shows the hand of an officer hanging by his side with the signaling device in position, both lights turned off;

Fig. 4 shows a side elevation of the signaling device;

Fig. 5 is a front elevation of the same;

Fig. 6 is a diagrammatic view of the signaling system with the red light projecting indicating "danger" or "stop", with two mercury switches in relative position;

Fig. 7 is a diagrammatic view showing the green light projecting, indicating "safety" or "go", with two mercury switches in a relative position;

Fig. 8 is a diagrammatic view with both lamps turned off, and two mercury switches in a relative position;

Fig. 9 shows the red light projecting indicating "danger" or "stop", with one mercury switch in a relative position;

Fig. 10 shows the green light projecting indicating "safety" or "go", with one mercury switch in a relative position;

Fig. 11 shows both lamps turned off, with one mercury switch in a relative position.

In describing the invention and apparatus, 10 indicates two sets of signaling apparatus, only one of which is shown. Each set is provided with two lamps 11 and 12 secured to a suitable harness 13 which is mounted on the officer's hands 14, that is, each hand is provided with the signaling apparatus which permits signals to be given as freely as ordinary hand signaling and with the varicolored lights a perfect signaling system is provided for night or foggy service. The lamps 11 and 12 are located in such relation to the hand and arm that a certain colored light will indicate a signal when the hand is in a certain position. To accomplish this the lamps are set approximately 90° apart on the hand harness 13. The hand harness 13 is preferably made of a high grade leather composed of two bands 15 and 16 held together by the straps 17 and 18 which are riveted to the hand bands 15 and 16. The hand bands can be secured together by adjustable brackets or any suitable device.

100

The lamps 11 and 12 are supplied with electrical current from a suitable source 19 shown in diagram. The electrical current is controlled by the swinging of the arm 20 from the body 21 of the officer. Two mercury switches 22 and 23 are enclosed in a suitable box 24 having a cover 25 held in position by screws. The mercury switch bulbs are so mounted in the box as to withstand jar and vibrations of the signaling operation.

One of the main embodiments of the invention is to provide a method or signaling light by the movements of the hands and arms of the traffic officer; that is, when the officer raises his hand in the vertical position and his arm in the horizontal plane the red light or "danger" will come into view and when the arm is bent V shape with the hand in the horizontal position, the green light or "go" will come into view. If there is no traffic passing, the hands are dropped to the sides and both the red and the green lights go out, thereby saving the electrical current and cutting down the cost of maintenance.

When the red light is on or lighted the contact is determined by the position of the switch which is in the same position for natural signaling by hand. In the Figure 6 the red light is on and the green light is off. The red light indicates "danger" or "stop" for on-coming traffic, while the green light indicates "go" or "safety". To throw on the red light and turn off the green light the mercury switch bulbs have to be located in a certain position, as shown in the diagram Fig. 6. In the diagram Fig. 6 the red light is on showing "danger" signal and the green light is off. When these lamps are in this position the mercury bulbs 22 and 23 are in a vertical position with the mercury 26 and 27 in the lower ends of the tubes 22 and 23. It can be readily seen that the mercury 26 surrounds the ends of the electrodes 28 and 29 making a contact which allows the current to pass to the filament of the lamp 11 through the lines 30, 31 and 32.

The electrodes 33 and 34 located in the mercury bulb 23 show the mercury 27 in such a position that no contact is made and the green light is off.

In Figure 7 the green light 12 is on indicating "go" or "safety" and the red light is off. To accomplish this function the hand of the officer is moved to bring the mercury bulbs 22 and 23 with a horizontal position showing the mercury 26 and 27 along the side of the bulbs. The mercury 27 covers the electrodes 35 and 36, thereby making a contact to throw in the green light for "go" or "safety". The current from the source 14 passes through the lines 37 and 38 thereby completing the circuit. In this view it will be seen that the electrodes 28 and 29 are not covered

by the mercury, therefore no contact is made and the red light is off.

In the Figure 8 both lights 11 and 12 are off showing that both hands of the officer are hanging by his side, and under the condition it is seen that the electrodes in both sets are in such a position that no contacts are made, indicating that both lamps are out, which conforms to the natural traffic controlling position of the hands and arms.

It is understood that three functions of the lamps and the arms are illustrated in the Figures 6, 7 and 8, indicating a "stop" signal in which a red light is shown and the officer's arm is in a horizontal position and his hand is in an approximately vertical position. In the Figure 7 the officer's arm is bent back upon itself with the hand in the horizontal position with the green light showing, indicating "go" or "safety". In Figure 8 both lights are out due to the officer's hands hanging downwardly by his sides with both lights out and indicating no traffic.

The Figures 9, 10 and 11 show a modified construction of my invention which is as effective in every way as the previous apparatus, but is much cheaper to manufacture. The difference in the layout is that the "stop", "go" and no traffic signals can be accomplished by one mercury switch in the following manner. In Fig. 9 as also in 10 and 11 the bulb 40 is provided with three electrodes 41, 42 and 43. In the Figure 9 the tube is in the vertical position with the mercury 44 in the lower end connecting up the electrodes 41 and 43 which energizes the lamp 11 and shows the red for "danger", while the electrode 42 leading to the green light is disconnected.

In the diagram 10 the mercury tube 40 is in the horizontal position, connecting up the electrodes 41 and 42 which energizes the lamp showing green for "go" or "safety", while the electrode 43 leading to the red light is disconnected.

In the Figure 11 the mercury bulb is in the inverted position showing that all the electrodes are disconnected, which indicates no traffic.

In operation the lamps 11 and 12 secured to the harness is fastened to the hands of the officer, one set of apparatus secured to each hand, both receiving their energy from a single electrical source. This, however, is not necessary, but it is the preferable way. In directing traffic the officer can use either hand as the conditions require. To indicate "stop" or "danger" the arm is raised to a horizontal position with the hand in a vertical position, at which time the position of the switch will throw in the red light as required. To indicate "go" the officer bends his arm back upon itself with the hand in the horizontal position, while by the position of the hand and the mercury switch the green light is thrown in indicating "go" or "safe-

ty" while the red light is off. When no traffic takes place, both hands and arms of the officer are hanging by his sides, and by the position of the arms and the mercury switches both red and green lights are off.

In accordance with the provisions of the patent statutes, I have described the principle of operation of my invention, together with the apparatus which I now consider to represent the best embodiment thereof, but I desire to have it understood that the apparatus shown is only illustrative and that the invention may be carried out by other means.

What I claim as new and desire to secure by Letters Patent of the United States, is:

In a road arm and hand signaling device, a hand harness, means for mounting the harness on the hand of the operator, a casing having a red lens, a casing having a green lens, a lamp mounted in each casing adapted to illuminate the lens, circuits for the lamps and a source of electrical energy, means mounting the first mentioned casing on one side of the harness, means mounting the second mentioned casing on the opposite side of the harness, at substantially a right angle to the first casing, switch means for automatically closing the circuit to the lamp in the first mentioned casing when the arm and hand of the operator are raised to an upright position, and for closing the circuit to the lamp in the second mentioned casing and opening the circuit to the lamp in the first casing when the hand and forearm of the operator is bent back over the upper arm, and means for opening the circuit to both lamps when the arm of the operator is dropped to the side, all three movements conforming to the natural movements of the hand and arm for regulating traffic.
